UNITED STATES PATENT OFFICE.

JOHN LEATHER, OF WATERBURY, CONNECTICUT.

LINGERIE CLASP.

Application filed July 18, 1921. Serial No. 485,535.

To all whom it may concern:

Be it known that I, JOHN LEATHER, a citizen of the United States, and a resident of Waterbury, county of New Haven, 5 and State of Connecticut, have invented certain new and useful Improvements in Lingerie Clasps, of which the following is a specification.

This invention relates to clasps, and 10 more particularly to lingerie clasps worn by ladies upon the ribbons or shoulder straps of their garments, such as corset covers, brassierès, chemises, etc.

In the modern style of women's dress, 15 the fashion is to make such shoulder straps of extremely thin fabric. The common forms of lingerie clasps have proven unsatisfactory when worn upon such straps, because they are designed for use on thick 20 fabric. Consequently these clasps either slip along the straps, or the straps have a tendency to crowd to one side in the clasps, and become disarranged, wrinkling the material, and in some cases even causing the 25 straps to become torn.

One object of the present invention is to overcome the above mentioned objections by constructing a lingerie clasp that will not only have a greater gripping power, but in 30 which the grip will be more uniformly distributed along the length of the clasp. With a clasp so constructed, the very thinnest of fabrics will be securely and neatly held in position, without the slightest danger of 35 wrinkling, tearing or slipping.

Another object is to provide a clasp which can be readily attached and detached by the wearer by operations involving the use of one hand only.

40 A further object is to provide a clasp that will be strong, durable, and attractive in use, and which may be rapidly and cheaply manufactured from sheet metal, without employing expensive tools or complicated machinery.

With these and other objects in view, there are illustrated in the accompanying drawings, several convenient forms in which the invention may be embodied.

50 In the drawings,

Figure 1 is a perspective view of a preferred form of clasp, shown in "open" position.

Figure 2 is a side view of the clasp shown 55 in "closed" position.

Figure 3 is a section taken along the line

3—3 of Figure 2, looking in the direction of the arrows, and showing two fabric straps gripped by the tongue and plate of the clasp.

Figure 4 is a view showing the manner 60 in which the clasp is worn upon the person, two clasps being shown in position upon corresponding shoulder straps of the garments.

Figure 5 is a top view of a slightly modified form of clasp. 65

Figure 6 is a section, on an enlarged scale, taken along the line 6—6 of Figure 5.

Figure 7 is a top view of another modified form of clasp embodying the principles 70 of the invention.

Figure 8 is a section, on an enlarged scale, taken along the line 8—8 of Figure 7.

Referring now to the drawings, the first embodiment of the invention is shown in Figures 1 to 4. In this embodiment, the 75 clasp consists of two main parts—the base plate 1 and the tongue 2—the entire clasp being preferably constructed by stamping from a single piece of metal, which is afterwards bent into shape. 80

The plate 1 is integrally joined to the tongue 2 by the resilient curved end section 3. At its opposite end the plate 1 terminates in a curled-over resilient catch member 4. This catch member is shaped like a hollow 85 cylinder, and its extremity 5 lies parallel to and in contact with the plate 1—this close contact being necessary to prevent the fabric from catching under the extremity 5 and becoming torn. 90

In order to secure a firm grip upon the fabric, longitudinal ribs 6 and 7 are formed in the plate 1 and tongue 2 respectively, and these ribs extend from the end section 3 to the catch member 4 of the clasp. The upper 95 face of the plate-rib 6 is shaped so that it fits within the under face or groove of the tongue-rib 7. As clearly illustrated in Figure 3, when the clasp is closed, the fabric within the clasp is not in a straight line, as 100 in most clasps, but has a double curvature, including two flat side portions and a curved central portion. This "double curvature" has been found to be most effective in preventing slippage of the fabric, and as the 105 ribs 6 and 7 extend the full width of the fabric, it will be evident that the grip will be uniformly distributed. Two fabric straps 10 and 11 are shown in Figures 2 to 4, but it will be understood that three or more may 110 be employed, if desired.

The tongue-rib 7 is extended, as shown at

8, slightly beyond the ends of the flat sides of the tongue,—this extension 8 overlying the inner edge of the catch 4, when the clasp is in open position.

For locking the tongue to the catch, the latter is provided with a cut-out portion 9, preferably circular in shape, as shown in Figure 1, into which the tongue extension 8 is adapted to snap, when the tongue is 10 pressed downwardly upon the catch 4. After the tongue extension has snapped into the cut-out 9, the catch expands again, and holds the tongue securely locked, in the closed position, as shown in Figure 2.

It will be apparent from the above that the fabric is held so firmly by the clasps, it cannot crowd to one side and become crumpled or wrinkled. Moreover, the danger of tearing is reduced to the minimum 20 because the stress on the fabric is uniform and not localized at any one point.

When it is desired to put on a clasp, it is merely necessary to place it around the lingerie straps and to push the tongue and 25 plate together, with the thumb and forefinger of one hand, until the tongue-extension 8 snaps under the cut-out portion 9 of the catch. The clasp is then in its locked position—as shown in Figures 2 to 4.

When it is desired to take off the clasp, it is only necessary to flex the base plate of the clasp slightly by placing the thumb under the base plate, and then pull down the 30 ends of the clasp with the first and second fingers of the same hand. The resiliency of the base-plate and the spring action of the curved end section 3 will release the tongue extension 8 from the catch 4 and cause the tongue to fly open. The clasp 35 may then be easily removed from the straps.

As clearly shown in Figure 4, the clasps are generally worn in pairs. In this view, an outer garment 12 covering an undergarment 13 are shown, each being provided 40 with straps 10 and 11 passing over the shoulders of the wearer. Two clasps 14 serve to keep these straps 10 and 11 together in symmetrical relation, and at the same time prevent the garments from 45 working around to one side. If desired another pair of clasps may also be worn upon the back of the wearer, but ordinarily 50 a single pair of clasps will be sufficient.

In the two modified forms of clasps illustrated in Figures 5 to 8, the ribs on the tongues and plates are of somewhat different construction from the corresponding ribs on the clasp shown in Figures 1 to 4.

The ribs 15 and 16 of the tongue and plate 60 of the clasp shown in Figures 5 and 6, have flat oval shaped portions 17 and 18 formed thereon intermediate the ends thereof. The top of the flat oval section 17 on the tongue, forms a convenient and appropriate location for ornamentation, monograms, or 65

other inscriptions the oval shaped portions 17 and 18 not only enhance the gripping power of the ribs 15 and 16 but are of considerable assistance in preventing sidewise slipping of the clasp across the fabric straps. 70

In the form of clasp illustrated in Figures 7 and 8, the ribs 19 and 20 are made of uniform rectangular section throughout their length. This embodiment is particularly adapted to receive ornamentation 75 and inscriptions, which may be engraved upon the flat surface of the wide rib which extends the full length along the top of the tongue.

An important advantage of the clasps 80 made in accordance with this invention is that they may be opened and closed without moving the tongue sideways across the base plate, which movement would be likely to injure the fabric. The clasps may be 85 closed by a vertical movement of the tongue, and may be opened by vertically flexing the base.

This novel method of engaging and disengaging the tongue by simple vertical flexing 90 movements, is of considerable commercial importance. Since horizontal flexibility is not required, the tongue may be made of wider, thicker, and stronger material, and thus a larger number of fabric straps may 95 be gripped in the same size of clasp the number being limited only by the height of the cut-out in the clasp.

The clasps disclosed herein are preferably 100 made from brass,—they may afterwards be electroplated with gold. Suitably tinted celluloid may also be employed with success.

While there has been disclosed in this specification several preferred forms in which the invention may be embodied, it is 105 to be understood that the same are shown merely for purposes of illustration, and that the invention may be modified and embodied in various other forms without departing from its spirit; in short, the invention is 110 not limited to the specific disclosure herein presented but includes all the modifications coming within the scope of the appended claims.

Having thus described the invention, what 115 is claimed as new, and for which Letters Patent is desired is:

1. In a lingerie clasp, a resilient base section, a ribbed tongue integral therewith and movable perpendicular thereto, said 120 base section having a locking and tongue-centering catch, the end of the tongue-rib extending beyond the end of the tongue, and adapted to lock the tongue to the base section when the tongue is pressed vertically 125 downward upon the catch.

2. In a lingerie clasp, a base section, a tongue joined thereto, said base section having a rib interlocking with a rib on said tongue to grip a lingerie strap therebetween, 130

a catch having a locking recess mounted on the end of the base section, the tongue-rib being extended beyond the end of the tongue, and adapted to overlie the catch in 5 open position, and to be locked within the catch recess when the clasp is in closed position.

3. In a jewelry clasp, the combination with a resilient base section joined to a 10 tongue, of a catch rigidly mounted on the free end of the base section, and formed integral therewith, the free end of said catch being in contact with and supported by said base, said tongue being locked by vertically 15 pressing it down upon the catch, said tongue being released by vertically flexing the base section, said tongue and base section being adapted to tightly grip a thin fabric strip therebetween when said tongue is pressed 20 down upon said catch.

4. In a lingerie clasp, a base section, a tongue, said tongue and base section being provided with interlocking ribs, said ribs having flattened portions intermediate their 25 ends whereby they assist in gripping lingerie straps therebetween and serve to display ornamentation.

5. In a lingerie clasp, a base section, a tongue joined to said base section, means for 30 locking the free end of the tongue to the base section, said base section and tongue having cooperating ribs for engaging a lingerie strap between the base section and tongue, said tongue being released from said 35 base section by vertically flexing the base section, said locking means lying in contact with and supported by said base section.

6. A clasp for holding lingerie straps comprising a base section and a tongue connected therewith at one end, the other end 40 of said base section being bent into the form of a cylinder to form a catch for said tongue, said cylinder being curled over into contact with the base section to prevent the lingerie 45 straps from slipping under said catch.

7. In a lingerie clasp, a base section having a recessed catch at one end, and a resiliently supported tongue at its other end, said tongue having a rib extended longitudinally 50 beyond the end of the tongue, and being adapted to be snapped into the recess of the catch and locked to the base section.

8. In a lingerie clasp, a base section, a tongue connected therewith at one end, said 55 base having its other end bent over into contact with the base section to form a catch member for locking the tongue.

9. A lingerie clasp comprising an elongated metal strip bent upon itself to form

a base section and a tongue, the base section 60 having a cylindrical catch with a circular cut-out recess on its inner side, said tongue having a raised extension adapted to be detachably locked in said recess.

10. A lingerie clasp comprising an elongated metal strip bent upon itself to form a base section and a tongue, the base section having a catch with a cut-out recess on its inner side, said tongue having a raised extension adapted to be detachably locked in 70 said recess.

11. A jewelry clasp comprising an elongated metal strip bent upon itself to form a base section and a tongue, said base section having a catch on its free end provided 75 with an inwardly extending cut-out recess, said tongue being provided with a rib, said rib having a portion extending beyond the free end of said tongue and locking under the recess on said catch for centering the 80 tongue on the clasp.

12. In a lingerie clasp, a base section, a tongue, and means for locking the tongue to the base section, a rib on said tongue, said rib having a flat portion for receiving 85 ornamental inscriptions and for enhancing the gripping power of the rib.

13. In a lingerie clasp, a base section, a tongue, and means for locking the tongue to the base section, a rib on said tongue, said 90 rib having an oval flat portion for receiving ornamental inscriptions for enhancing the gripping power of the rib and for preventing sidewise slipping of the clasp over the straps. 95

14. In a lingerie clasp, a base section, a tongue connected therewith at one end, a catch on the other end of said base section, said catch being adapted to spread outwardly when the tongue is pressed down 100 upon it, but being supported against spreading inwardly when pressure is exerted upon it, said tongue being locked by vertically pressing it down upon the catch, and being released by vertically flexing the base 105 section.

15. In a lingerie clasp, a base section, a tongue connected therewith at one end, the other end of said base section being bent over into contact with said base section and 110 forming a catch for said tongue, said tongue being locked by pressing it vertically down upon said catch and being released by vertically flexing said base section.

In testimony whereof, I have affixed my 115 signature to this specification.

JOHN LEATHER.
